UNITED STATES PATENT OFFICE.

HARRY F. SMITH, OF DAYTON, OHIO, ASSIGNOR, BY MESNE ASSIGNMENTS, TO THE GAS RESEARCH COMPANY, OF DAYTON, OHIO, A CORPORATION OF OHIO.

METHOD OF FUEL AGITATION.

1,417,637.

Specification of Letters Patent. Patented May 30, 1922.

Application filed August 1, 1918. Serial No. 247,877.

To all whom it may concern:

Be it known that I, HARRY F. SMITH, a citizen of the United States of America, residing at Dayton, county of Montgomery,

5 State of Ohio, have invented certain new and useful Improvements in Methods of Fuel Agitation, of which the following is a full, clear, and exact description.

This invention relates to fuel agitation and more particularly to a method of fuel agitation in which the entire fuel bed is lifted bodily from the grate upon which it rests and is thoroughly stirred up, the use of the various complicated stoking or agitating 15 mechanisms now on the market being dispensed with.

One of the objects of this invention is to provide a very simple method of fuel agitation and an equally simple form of apparatus for carrying that method into effect.

20 Other objects and advantages will be apparent from the description of the invention set out below, reference being made to the accompanying drawing.

25 One of the biggest difficulties in gas producer operation is the proper maintenance of the fuel bed. This difficulty is of course present to greater or less degree in all forms of apparatus using a fuel bed which must be continuously replenished and from which the ashes must be removed. Heretofore numerous mechanical devices, such as shaking grates, mechanically operated stirring bars and the like, have been used for this 30 purpose. These devices, although comparatively complicated, have been successful in ordinary fire box or furnace operation. They have not, however, so far as known to me, been successful in gas producer operation. It must be remembered that in a gas 35 producer the fuel bed ordinarily has a thickness of from three to six feet and it is quite obvious that the ordinary mechanical agitating devices are entirely inadequate for 40 securing a proper conditioning of such a thickness of incandescent carbonaceous material.

45 It was primarily to provide for the satisfactory agitation of the fuel bed in a gas producer that I devised the method of agitation and the apparatus for carrying that method into effect which constituted the subject matter of the present invention. For 50 purpose of convenience and greater clearness this invention will be described in con-

nection with a conventional type of producer; but it is to be expressly understood that my invention is not thus limited in its applicability.

This method of fuel agitation consists broadly of collecting an explosive mixture, 60 igniting that mixture and applying the resulting explosive effect beneath the fuel bed. In this manner the fuel bed is lifted bodily from the grates upon which it rests and is 65 thoroughly agitated during its upward movement and as it settles back upon the grates after being lifted therefrom. For carrying this method into effect I made use of the apparatus illustrated in the accompanying 70 drawing.

In the drawing is disclosed a gas producer having a metallic shell 1 surrounding the generating chamber, a firebrick lining 2 therefor, a grate 3 for supporting the fuel, 75 a fuel feeding device 4, an air intake pipe 5, and a gas off take pipe 6. This structure is that of the conventional up-draft, or suction, type of producer.

Located adjacent the bottom part of the 80 producer is an explosion chamber 10 having an outlet 11 which in turn opens into the space 7 at the lower part of the producer 1, below the grate 3. If an explosive mixture is collected within the chamber 10 85 and ignited the explosive effect will act through the outlet 11 and space 7 upon any fuel that may be resting on the grate 3. Leading into the upper end of the chamber 10 is an inlet passage 12 the upper end of 90 which is divided into a plurality of passages 13 and 14. The passage 14 has leading thereinto a pipe 15 which is connected with a source of explosive mixture, the mixture being fed through the pipe 15 under any desired 95 pressure.

Connecting the passages 13 and 14 is a port 16 controlled by the valve 17. The valve 17 is normally held against its seat by means of the spring 19 which surrounds the 100 valve stem 18. Adjustably attached to the outer end of the valve stem and cooperating with the spring 19, to vary the tension thereof, is a nut 20. By means of this adjustable nut 20 the tension of the spring 19 may be 105 varied as desired.

Pivoted to the wall of the inlet passage 12 is a yoke 30 adapted to contact with the end of the valve stem 18. Rotatably mounted on the explosion chamber, adjacent the yoke 30, 110

is a cam 31 adapted to cooperate with the yoke 30 and upon rotation thereof to swing said yoke about its pivot and force it into contact with the end of the valve stem to thus 5 lift the valve 17 from its seat and open the port connecting passages 13 and 14. When the valve is in this position an explosive mixture may pass through the pipe 15 and passage 14 into the passage 13 and thence 10 through the inlet passage 12 to the explosion chamber 10.

Inserted through the wall of passage 13 is a spark plug 40 the inner terminals of which are situated within the passage. Connected 15 to the spark plug 40 is a coil 41 having a switch 42 connected therewith. Proper manipulation of the switch 42 will cause the passage of a spark within the passage 13 to ignite the explosive mixture within such passage and then ignite the explosive mixture 20 within the chamber 10.

When it is desired to agitate or stir up the fuel upon the grate 7, the cam 31 is rotated to swing the yoke 30 about its pivot and thus 25 lift the valve 17 from its seat permitting the flow of explosive mixture into the chamber 10. When the desired quantity of explosive mixture has been collected in the chamber 10 the switch 42 is actuated to ignite that explosive mixture. The explosive effect resulting 30 from thus igniting the explosive mixture in chamber 10 will act through the outlet 11 and space 7 upon the fuel on the grate 3. As a result of such explosive effect the fuel bed 35 will be lifted bodily from the grate and thoroughly agitated both during its upward movement under the effect of the explosion and during its return to the grate. The term fuel bed has been used herein to designate the 40 entire mass of fuel and ashes resting upon the grate 3. In actual practice this fuel bed generally consists of a lower or ash zone resting upon the grate, an intermediate or incandescent zone above the ash zone and an upper 45 or distillation zone, above the incandescent zone, consisting of the fresh fuel which is added from the fuel feeding device 4. The explosive effect resulting from igniting the explosive mixture in the chamber 10 will be 50 exerted upon the ash zone of the fuel bed, from beneath the grate, and is of such nature that it will suddenly raise the entire fuel bed and, after short duration, will as suddenly allow the fuel bed to settle back upon the 55 grate. As a result the fuel bed will be thoroughly broken up, but the explosive effect is

of such short duration that the ashes within the ash zone will not be blown through the fuel bed and out through the offtake pipe 6.

It has been suggested heretofore to use 60 blasts of compressed air or steam for agitating a fuel bed. I have found, however, that these methods are less effective than the method disclosed by me. In order to secure a proper breaking of masses of coked material and such like, and to thoroughly agitate and stir up the fuel bed I have found the 65 instantaneous blow resulting from an explosion superior to the slower acting blast of compressed air or steam.

While the method herein described, and the form of apparatus for carrying that method into effect, constitute preferred embodiments of the invention, it is to be understood that the invention is not limited to this precise method and form of apparatus, and that changes may be made in either without departing from the scope of the invention which is defined in the appended claims.

1. The method of agitating the fuel bed 80 within a gas producer or the like, which consists in igniting an explosive mixture, and applying the resulting explosive force to the underside of the ash zone of the fuel bed, to lift the fuel bed bodily.

2. The method of agitating fuel which consists in collecting an explosive mixture, igniting that mixture and applying the force of the explosion to the under side of the ash zone of the fuel bed, the explosive effect being sufficient to raise the entire fuel bed bodily, but of such duration as to not drive ashes from the ash zone through the fuel bed.

3. The method of agitating fuel which consists in collecting an explosive mixture in a chamber, igniting the mixture, and applying the force of the explosion to the under side of the fuel bed.

4. The method of agitating the fuel bed within a gas producer or the like, which consists in collecting an explosive mixture in a chamber separate from, but having an outlet opening into, the producer or the like; igniting the collected mixture within the chamber; and applying the force of the resulting explosion to the under side of the fuel bed.

In testimony whereof I affix my signature.

HARRY F. SMITH.
